Primary Examiner — Marissa J. Cash
Assistant Examiner — William B Melliar

(57) **CLAIM**

The ornamental design for a bracket for headgear as shown and described.

DESCRIPTION

FIG. 1 is a perspective view showing an embodiment of the new design for a bracket for headgear;

FIG. 2 is a front view thereof;

FIG. 3 is a top view thereof;

FIG. 4 is a left side view thereof;

FIG. 5 is a right side view thereof;

FIG. 6 is a bottom view thereof;

FIG. 7 is a rear view thereof;

FIG. 8 is a perspective view showing another embodiment of the new design for a bracket for headgear;

FIG. 9 is a front view thereof;

FIG. 10 is a top view thereof;

FIG. 11 is a left side view thereof;

FIG. 12 is a right side view thereof;

FIG. 13 is a bottom view thereof; and,

FIG. 14 is a rear view thereof.

The broken lines shown in the drawings depict portions of the bracket for headgear that form no part of the claimed design. The dot-dash broken lines immediately adjacent the shaded surfaces in FIGS. 6 and 7 depict the bounds of the claimed design and form no part thereof.

1 Claim, 14 Drawing Sheets
